UNITED STATES PATENT OFFICE.

LOYD I. ALDRICH, OF PEORIA, ILLINOIS, ASSIGNOR TO HART OIL BURNER CO., OF PEORIA, ILLINOIS, A CORPORATION OF ILLINOIS.

COMBUSTION APPARATUS.

Application filed March 7, 1924. Serial No. 697,508.

My invention relates to liquid fuel atomizing devices, and more particularly to means for controlling the fuel mixture thereof.

5 The object of my invention is to provide improved controlling mechanism for a combustion apparatus.

Another object of my invention is in the provision of a liquid fuel mixing device of 10 the blower type, having related fuel and air control mechanism adapted to regulate the fuel mixture.

A still further object of my invention is in the combination with a liquid fuel atomizing device having an auxiliary air blast of 15 flame controlling mechanism, including an automatic damper member and a fuel control valve.

Other objects of my invention will appear 20 in the following specification taken in connection with the annexed drawings; in which

25 Fig. 1 is a plan view from above of a portion of my atomizing device, showing in detail the arrangement of the damper member.

Fig. 2 is a side elevation of Fig. 1.

Fig. 3 is a side view of the device showing 30 the general relation of the fan and housing to the main discharge and ignition portions of the device.

Fig. 4 is a rear elevation showing generally my liquid fuel atomizing device; and

35 Fig. 5 is an enlarged detail of the fuel control means.

Referring to the drawings, in Fig. 4, I have shown a general view of my liquid fuel atomizing device, which forms the subject matter of a co-pending application, Serial #633,272, filed April 19, 1923.

The present application is directed mainly to an arrangement of controls for regulating the flame or fire produced by the atomizer.

45 The atomizing device per se is the same as the one shown and described in the above-mentioned application, and for that reason only a general description of the parts and operation will be given.

50 In Figure 4 a general view of the liquid fuel atomizer shows a power means for the device, namely an electric motor 10. There is a flexible coupling 11 connecting the power

means with the main shaft 12 of the fuel atomizing and feeding device, which is made 55 up of the following portions:

The shaft 12 is disposed horizontally and has a fuel pump 13 connected to the outer end, said pump having a fuel inlet pipe 14 in connection therewith. An air pump 15 is

60 also mounted upon the main shaft 12, said air pump being adapted to produce a considerable air pressure for the purpose of atomizing the liquid fuel. The above-men-

tioned air compressor has been described in detail in my co-pending application, and includes briefly an eccentric roller having a plurality of cups upon its periphery, rotat-

65 ing in a chamber partially filled with a liquid, whereby, through centrifugal action air is taken into the so-called cups placed under

compression, due to the eccentric mounting of the roller, and forced out under an ex-

tremely high pressure. This air compressor 70 forms no part of the present application, other than to show the general operation of

75 the atomizing device. A fan housing 16 houses a fan or blower 17 which is disposed upon the horizontal shaft 12, and provides

80 the added draft through the blast tube 18 to the combustion chamber (not shown). The fuel pump 13, before mentioned, supplies fuel to the needle valve indicated at 19 in

85 Figure 5. The fuel from said pump passes through the pipe 20 into the valve portion 21, wherein the flow may be regulated by movement of the handle 22, said fuel then

85 being projected into the atomizing chamber or venturi 23. From the air pump 15 the

90 high-pressure air is forced through the pipe 24 to the atomizing chamber or venturi 23, where a substantially complete atomization of the fuel occurs, the resultant mixture

95 passing through the pipe 25 to the right-angled elbow 26 located at the lower portion of the fan housing. Theoretically there should be a complete atomization of the fuel

100 within the venturi. However, should there not be such a complete atomization, any fuel not completely atomized will be caught in the small sump 27 just below the elbow 26, and returned through the small pipe 28 to the air pump, this excess fuel acting as a means for

105

replenishing the liquid in the air pump, which requires a certain amount of additional fuel as a lubricating medium. The

major portion of the fuel mixture is of course completely atomized and passes through the tube 29 disposed within the draft tube 18 to the nozzle 30, from whence it is projected into the combustion chamber (not shown).

Means for igniting the projected fuel mixture is provided in a formal gas pilot tube 31 of conventional design, but in the 10 present instance said gas pilot is ignited by an electric spark, the points of which are shown at 32.

Having described briefly my liquid fuel atomizing device, said device forming the 15 basis of my co-pending application above noted, I will say that in the above device the atomized fuel mixture is projected into the combustion chamber (not shown) where it is ignited.

20 The fuel situation, as related to liquid fuel atomizing devices, makes it impossible for the consumer to always purchase for use the same grade of fuel. Although the present atomizing device or burner is adapted to 25 use a fuel oil of low specific gravity, this being the most desirable fuel not only because of cost, but also because of the high heating efficiency thereof, still in many instances—usually due to locality—it is necessary to use 30 a different grade of fuel; we will say, a fuel as light as distillate.

It may well be seen that although the atomizing device so far described might burn 35 a fuel of a certain grade efficiently, still if some other grade of fuel would have to be used, then a certain amount of regulation of the device would be necessary to procure the same efficiency in burning.

In other words, it is desirable to have a 40 device adapted to handle the various grades of fuel, and for this reason I have provided the following means for controlling the fuel mixture and consequently the flame or fire produced thereby.

45 One of my control means has been described, namely the control through the movement of the handle 22 of the fuel flow from the pump 13, and consequently the amount of discharge of said fuel into the 50 atomizing chamber or venturi 23. The above means is my regulating medium for the flow of fuel.

55 My fan 17 provides an ascertained blast through the tube 18 to the combustion chamber. This added draft has been found necessary in the present type of burner, but this draft must be regulated to efficiently co-operate, or rather assist in the combustion of the fuel used. In other words, a certain 60 amount of draft might be all right for one type of fuel, but in case another fuel were used, variation of this air blast would be necessary. To accomplish this varying of the fan blast to the combustion chamber, I 65 have provided a damper 33, fashioned in

a manner that it may pivot within the blast tube about the fuel discharge tube 29 disposed therein. This pivotal movement of the draft member 32 is provided by raising upon one side the surface 33 thereof, 70 and lowering upon the other side the surface 34 to permit passage of the fuel tube 29 therethru. Means for pivoting the draft member to the sides of the blast tube is obtained by the pivots 35 and 36, said pivot 75 36 being extended as at 37 to provide an arm whereon an adjustable weight member 38 is located.

The above described damper member is normally held in the closed position by the 80 weight 38 and in view of the unequal area thereof at opposite sides of the pivotal axis, the damper is caused to open as the pressure is built up by the blower in the duct 18, and automatically closes when the pressure 85 is relaxed. Thus when the blower is at rest the passageway through the duct 18 is closed and by proper adjustment of the weight 38 the opening of the damper may be delayed until sufficient pressure is built up to insure 90 that the air will be supplied to the combustion area in a blast. This valve or damper also serves, upon reduction of speed of the blower, to prevent back draft through the duct 18 and thereby prevents blowing out of 95 the pilot light.

I have provided a damper member not only for the above reasons, but also to regulate the air blast from the fan according to 100 the grade of fuel and flow thereof. I accomplish the above by means of the adjustable weight 38 which has a considerable movement along the arm 37. It may be seen that if the weight is disposed at the outer end of the arm 37, even with the fan rotating at its highest speed, the damper will not be forced to the position shown in Figure 2, but will only be moved to a position to permit a small air blast through the tube 18. Similarly, if the weight is moved 105 to the position shown in Figure 1, the blast of air from the fan will force it substantially to the position shown in Figure 2, where the entire fan blast will pass into the combustion chamber.

Taking into consideration my adjustment 110 of the valve 19 to control the flow of fuel, and the adjustable draft member, I am able not only to efficiently burn any grade of oil, but also—and more important—to control the size of fire within the combustion chamber.

This controlling of the size of the fire within the combustion chamber is very important, and for this reason the present type 125 of controls were developed.

To bring out the vital importance of controlling the size of fire within the combustion chamber, we must first understand the 130 operation of the present atomizing device

or burner within the well-known type of heating system—hot air.

- Fuel burning systems of the present type, wherein a fuel blast is forced into the combustion chamber, are sometimes at a disadvantage in the well-known hot air system of heating, in view of the fact that there is a certain amount of pressure forced into the combustion chamber of the heating system.
- Now, in hot air heaters, if the pressure of this discharge is excessive, and the furnace or combustion chamber has any leaks therein, there will be an escape, due to this excess pressure of gases into the air pipes, and hence into the house proper. The above difficulty is not present in hot water or steam systems; but in hot air heaters in order to have an efficiently operating burner of the present blast feed type, there must be some means of reducing the flame, and at the same time efficiently burning the fuel, the reduction of the size of fire being for the purpose of reducing the pressure forced into the com-

bustion chamber of the furnace to a point below the normal draft thereof. 25

It has been for the purpose of overcoming the above difficulty that the present method of control has been developed, whereby a reduction of the fuel flow may be counterbalanced by an adjustment of the air blast 30 whereby a smaller but just as efficient fire will result.

What I claim is:—

In an apparatus of the class described, the combination of a duct, a blower discharging into said duct a fuel supply pipe leading through said duct and having a discharge nozzle at the end through which atomized fuel is emitted, a valve in the duct pivoted on an axis which extends transversely through the supply pipe and having reversely formed recessed portions to embrace the supply pipe when the valve is in the open position. 35

In testimony whereof I affix my signature.

LOYD I. ALDRICH.
